FRANK OSMERA, OF WAUNETA, NEBRASKA.

CORN SHELLER.

Application filed August 28, 1924. Serial No. 734,660.

The invention relates to corn sheller attachments, and has for its object to provide means for eliminating noise, loss of time and expense of removing shelled corn from the baffle board upon which the shelled corn falls, when removed from the cob by the shelling mechanism of the corn sheller. It has been found that under favorable conditions the corn will slide downwardly on the conventional form of baffle board, which is stationary, but when the corn is damp it accumulates on the baffle board, preventing further operation of the sheller, until the lodged corn is removed. It has also been found that dirt or other foreign matter intermixed with the shelled corn will lodge the same as damp corn, therefore it is an object of the invention to provide an inclined baffle board, hingedly mounted and hingedly connected to the reciprocating separator box, which baffle board will oscillate and dislodge the corn therefrom.

A further object is to provide a connecting rod for the separator box comprising spaced arms, which arms terminate in a transversely disposed elongated, separable bearing connected to the crank of the crank shaft, thereby materially strengthening the bearing and connecting rod and obviating the difficulty found in connecting rods as at present used.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:—

Figure 1 is a longitudinal sectional view through a portion of a conventional form of corn sheller showing the baffle board applied thereto.

Figure 2 is a perspective view of a portion of the shaker box and the connecting rod.

Figure 3 is a perspective view of a portion of the separator box and the baffle board.

Referring to the drawing, the numeral 1 designates a conventional form of corn shell-

thereof. The corn, as it is shelled, drops onto the baffle board 3, and shaker box 4 in the usual manner. However it has been found that where the baffle board is stationary that damp corn or dirt collects thereon incident to the shaking operation, and it is necessary to dislodge the same therefrom from time to time. To obviate this difficulty the baffle board 3 is hingedly mounted at 5, and extends downwardly and is hingedly connected at 6 to an upwardly extending plate 7 carried by the end 8 of the separator box. Therefore it will be seen that the baffle board 3 will oscillate during the oscillation of the separator box. The separator box 4 is guided in its movement in the usual manner by means of members 9 carried thereby which are disposed in slots 10 in the sides of the corn sheller, therefore it will be seen that an elongated bearing connection 11 is necessary between the plate 7 and the lower end of the baffle board so that the shaker box will not be held against movement by the baffle board.

Extending transversely of the sheller 1 is the crank shaft 12 of a conventional form, which crank shaft is provided with a crank 13, on which is mounted a relatively long transverse bearing 13^a, preferably separable as shown, and which bearing 13^a is provided with upwardly inclined integral parallel arms 14, which are connected to the transverse rod 15 carried by the separator box. It has been found that the uneven forward and backward movement of the connecting rods of conventional forms of shellers soon wear the short box bearings carried thereby, and cause loss of time and expense incident to repair and upkeep. By providing the single elongated bearing and the arms 14 carried thereby, two independent bearing members are obviated, consequently the bearing will evenly wear and the alignment thereof will be maintained, which is not the case where two bearing members are used.

From the above it will be seen that a movable baffle board is provided for corn shellers, which will prevent the lodgement of corn and dirt thereon, consequently will obviate the stopping of the machine from time to time to remove the corn and dirt from the baffle board. It will also be seen that a single bearing member relatively long is provided for separator box which will obviate

the common difficulties incident to misalignment of two separate bearing members and rapid wearing thereof.

The invention having been set forth what is claimed as new and useful is:—

The combination with a corn sheller, a separator box, means for reciprocating the separator box, of a downwardly inclined baffle board, said baffle board having its upper end hingedly mounted, an upwardly extending rigid flange carried by the sepa-

rator box, a hinge connection between the lower end of the baffle board and the upwardly extending flange of the separator box, said last named hinge connection being a loose one whereby said flange of the separator box may move with the movement of the separator box and the baffle board may accurately swing during the movement of the separator box.

In testimony whereof I affix my signature.
FRANK OSMERA.
